PIERRE E. GUERIN, OF NEW YORK, N. Y.

DESIGN FOR A LAMP.

Design No. 17,667, dated August 30, 1887.

UNITED STATES PATENT OFFICE.

PIERRE E. GUERIN, OF NEW YORK, N. Y.

DESIGN FOR A LAMP.

SPECIFICATION forming part of Design No. 17,667, dated August 30, 1887.

Application filed November 17, 1886. Serial No. 219,211. Term of patent 3½ years.

To all whom it may concern:

Be it known that I, PIERRE E. GUERIN, of the city, county, and State of New York, have invented a new and original Design for Lamps, 5 of which the following is a specification.

The nature of my design is fully shown in the accompanying photograph, in which a perspective view of the lamp is shown.

The leading feature of my design is the body, 10 the same consisting of the body terminating at one end in a dolphin's head and at the other end in a volute.

A is the base. B is an ornamental standard on the base, the upper end of said standard being in the form of diverging leaves, forming a leaf top, C. The fount D, above said leaf top, terminates at one end in a volute, E, and at the other end in a dolphin's head, F. Extending vertically upward from the volute E 15 is a rod, H, which terminates at its upper end in a crown shaped ring, H', having curved dependents. Extending laterally from the volute end of the fount is a scroll-bracket, K, on which is an ornamental cup, L, and above 20 said cup is the flaming torch M. An orna-

mental pendent, J, depends from the bottom of the fount at a point opposite the upright rod H.

Having thus described my invention, I claim—

1. The design for a lamp herein shown and described, the same consisting of the body terminating at one end in a dolphin's head and at the other end in a volute.

2. The design for a lamp, as herein shown and described, consisting of the base, the standard terminating at its upper end in a leaf top, the fount terminating at one end in a dolphin's head and at the other end in a volute, the scroll extending laterally from the volute 35 end of the body, the ornamental cup on said scroll, and the flaming torch on said cup.

In testimony that I claim the foregoing as my invention I have signed my name in presence of two subscribing witnesses.

PIERRE E. GUERIN.

Witnesses:

PAUL GOEPEL,
MARTIN PETRY.
